UNITED STATES PATENT OFFICE

EYVIND FINSEN, OF ROCHESTER, NEW YORK, ASSIGNOR TO GLEASON WORKS, OF ROCHESTER, NEW YORK, A CORPORATION OF NEW YORK

GEAR-GENERATING MACHINE

Application filed October 12, 1928. Serial No. 312,173.

The present invention relates to a machine for generating gears and particularly to a machine for generating bevel gears of the type in which the generating roll is effected in part by gear segments.

The primary purpose of this invention is to provide a machine of the type described which will be more universal than similar machines of previous constructions, in other words, which will be capable of cutting a greater range of gears than previous machines of the same type.

A further object of this invention is to provide in a machine of the character described a construction that will insure in the highest degree a uniform and steady operation of the moving parts avoiding any slight irregularities in the motion of the machine which might adversely affect the tooth finish obtained on the gears generated.

Other objects of the invention will appear hereinafter from the following description and from the recital of the appended claims.

Figure 1 is a perspective view of a straight toothed bevel gear generating machine constructed according to a preferred embodiment of the present invention, parts of the frame being broken away to show more clearly certain features of the improved construction;

Figure 2 is a front elevation of the generating cams and associated parts for oscillating the cradle;

Figure 3 is a section through the machine and parts shown in Figure 2;

Figure 4 is a side elevation of the generating segments and showing particularly the mounting for the crown gear segment;

Figure 5 is a view of the crown gear segment and its mounting taken at right angles to Figure 4 and showing, also, details of the mounting of the rollers which serve to maintain the two segments in mesh as they roll together;

Figure 6 is a detail view showing in plan the rollers and their mountings and showing the gear and crown gear segments in section; and

Figures 7 and 8 are detail views in elevation and in plan, respectively, showing an al-

ternative form of roller mounting which is particularly advantageous when a pinion is being cut on the machine and the rolling motion is effected in part by a pinion segment.

The present invention provides an improvement over the machines of Patents Nos. 1,660,502 and 1,679,809 and of the copending application of James E. Gleason et al., No. 220,785, filed September 20, 1927, as regards the mechanism for producing the generating roll. The present invention is illustrated in connection with a machine for generating straight tooth bevel gears but it will be understood that it is equally applicable to machines for generating curved tooth bevel gears.

In a machine of the type to which the present invention relates, the relative generating roll between tool and blank is produced by oscillating a cradle or carrier on which either the tool or blank is mounted and simultaneously effecting a rotation of the blank on its axis through the rolling engagement of a gear segment, to which the blank spindle is connected, with a gear segment having a relatively fixed relation to the tool. In most instances, this second segment is mounted on a relatively fixed part of the machine and the work head or support is mounted on the cradle and it is in connection with a machine of this particular form, a machine in which "all the roll is on the work", that the present invention is illustrated.

A machine of the type described has the advantage of essential simplicity, requiring a minimum number of operating parts. Early efforts at building machines of this character, however, were restricted to the manufacture of machines which were intended purely and simply for high production work where a machine could be kept busy turning out in quantity the same gear for, with the earliest construction of machines of this type, it was necessary to change both the work segment and the relatively fixed segment in order to cut gears of different pitch cone angles and these segments are costly. In an effort to universalize this type of machine so as to make it economically practical to cut gears of various cone angles on the same machine, changes were proposed and made in the

nature of the gear segments controlling the roll. Efforts in this direction resulted in the invention described in the copending application of James E. Gleason et al., Serial No. 220,785 above referred to in which the present applicant is one of the joint inventors. The invention of this prior application provided means whereby gears of different dimensions might be produced on the same machine correctly and with a minimum of tool adjustment by changing the work segment only. But even with this last named invention, the range of the machine was still limited to the production of either gears or pinions because of the fact that there is a wide difference in the amount of roll required to fully generate the profile of a pinion tooth from that required to fully generate the profile of a gear tooth. It would be impossible to fully generate a gear tooth with a roll sufficient only for generating a pinion tooth and to use the same roll for generating a pinion as would be required to generate a gear would be wasteful in time, uneconomical and, therefore, impractical. Further if the long roll required for generating a gear were employed in generating a pinion, there would be a considerable danger of interference between the rolling parts and the stationary parts of the machine because the work head must be adjusted angularly on the cradle closer to the tools for generating a pinion than for generating a gear in order to bring the pinion blank into operative relation with the tools. As a result, despite the improvement constituting the invention of application No. 220,785, it remained the practice to still use separate machines for cutting gears and pinions.

Through the improvement of the present invention, it is possible, however, to produce both gears and pinions economically on the same machine. This is accomplished at the same time without any danger of interference between the work head and the relatively stationary parts of the machine during the generation of either type of gear.

With the present invention, two separate cams are provided for oscillating the cradle, the cam paths of which are of widely different conformation so that one cam is capable of rolling the cradle through a comparatively large angle as required when generating gears and the other cam is capable of rolling the cradle through a comparatively small angle only and is used when generating pinions. A single roller or follower is provided engageable selectively with either cam to transmit motion from either cam to the cradle.

With the present invention, further, the purpose of obtaining universality is forwarded as in application No. 220,785 by producing the blank rotation through a bevel gear segment which is attached to the blank

spindle and which has a pitch cone angle less than the pitch cone angle of the blank and a relatively fixed but resiliently mounted crown gear segment. Hence, only the work segment requires changing for cutting gears or pinions of different cone angles. The present invention constitutes, however, in this regard an improvement over the construction of the prior application mentioned in the mounting of the crown gear segment, this segment being mounted for pivotal movement. Through this pivotal mounting, a uniform steady operation of the machine is insured and at the same time all possibility of interference of any of the moving parts with any of the stationary parts during the roll is completely avoided.

Reference will now be had to the drawings for a more complete understanding of the principles of the present invention. A straight tooth bevel gear generating machine embodying in its construction the improvements of this invention is shown. 10 indicates the bed or frame of this machine. This bed or frame is provided at one end with an upright portion 12 which serves as a support for the oscillating cradle 13 on which the work head is mounted. The base or frame 10 serves as a support, also, for the tool carrier 15 which will preferably be made movable toward and from the work head in order to withdraw the tools from engagement with the blank for indexing and in order to feed the tools into depth and in order, also, to separate the tool from the work head far enough to take off a completed gear and chuck a new blank. The tool carrier carries two tool slides, one of which is to be seen at 16 and each of the slides carries a planing tool for cutting the gear tooth surfaces. The means for adjusting the tools and actuating the same and for actuating the tool carrier may be of the character described in the patent to Gleason et al. No. 1,660,502 of February 28, 1928, above referred to or of any other suitable type. It is to be distinctly understood that the present invention is not limited to the use on machines for producing straight tooth gears as it is usable, also, on machines of the character described in Patent No. 1,679,809 of August 7, 1928, to Bullock et al. above referred to and on machines of the type described in copending application No. 220,785 above referred to and on other types of machines, also, as will be obvious to those skilled in this art.

The work head carries the gear blank G to be generated. The gear blank may be secured to the work spindle by means of a draw rod, one end of which is seen at 18 (Fig. 1). In the machine illustrated, the indexing mechanism is of the notched-plate type. The type of indexing mechanism to be employed, however, has no relation to the present invention and any suitable type of indexing

mechanism may be used on my improved form of machine.

In the form of indexing mechanism shown, a notched-plate 19 is secured to the work spindles, the work spindle is journaled in a sleeve which is in turn journaled in the work head and the spindle and sleeve are connected together during cutting by a locking dog, such as shown at 20, which is mounted upon 19 an arm 21 which is secured to the sleeve above referred to. During cutting, the sleeve and spindle are locked together and for indexing, the sleeve and spindle are rotated relatively to each other. For a more complete description 15 of the operation of the indexing mechanism shown, reference may be had to Patent No. 1,660,502 above referred to.

The means for effecting the generating roll will be described now. Journaled in the 20 frame of the machine is a cam shaft 25. Keyed to this shaft is a large cam 26 provided with a closed track 27. A nut 28 serves to hold the cam 26 on the shaft. Secured to the outer face of the cam 26, as by means of 25 screws 29 is a second smaller cam 30 of the peripheral or open type. The periphery of the cam 30 which constitutes its cam path is of a different configuration from the cam track of the cam 26 and is so formed as to transmit 30 to the cradle 13 an oscillating movement through a much smaller angle, in one revolution of the cam shaft, than will be transmitted by the cam 26 in one revolution. The two cam paths are formed, however, so as to align 35 at one point, as at the point 32 indicated in Figure 2.

Pivottally mounted upon a stud 34 which is secured to the frame by suitable means, as the screw 35, is an arm 36. 38 designates a 40 connecting rod comprising the short arms 39 and 40 which are adjustably connected by the turn-buckle 41. The arm 39 is pivotally connected to the cradle 13 at 42. The arm 40 has a swivelled connection through the bolt 43 45 with a block 44 which is slidably adjustable in a T-slot 45 formed in the free end of the arm 36. Adjustments of the block 44 to vary the throw of the connecting rod 38 can be effected by rotating the screw 46 which has a 50 threaded connection with the block 44 and is secured to a plate 47 which is secured to the arm 36 by pins or screws and which forms one end wall of the T-slot 45.

The arm 36 is formed intermediate its ends 55 with an integral housing 50 of generally cylindrical shape. Mounted in the housing 50 is a cylindrical member 51 to the outer end of which is secured a cam roller 52. The cylindrical member 51 is mounted for axial 60 movement in the housing 50 in a direction parallel to the axis of the cam shaft 25 but is held against rotational movement in the housing by a key 53 which engages a suitable slot formed in the housing. The end 65 of the cylindrical housing 50 opposite to the

roller 52 is closed by a plate 55 which is secured to the housing by screws 56. The plate 55 is bored centrally to receive the stud of a screw 57, the threaded portion of which engages a correspondingly threaded opening tapped into the inner end of the cylindrical member 51. The screw 57 is unthreaded where it passes through the end plate 55 and is locked against axial movement in the end plate by its head 58 and a lock nut 59.

A hole 60 is formed in the frame or base 70 of the machine. The cam roller 52 is adapted to engage selectively either of the cams 26 or 30. When the screw 57 is turned to the limit of its movement in one direction, the cylindrical member 51 will be moved in the housing 50 to engage the roller 52 with one of the cams and when the screw 57 is turned to the limit of its movement in the opposite direction, the carrier 51 will be moved to bring the roller 52 into engagement with the track of the other cam. Before moving the roller from engagement with one cam to engagement with the other, however, the cam shaft 25 will be rotated to bring the point 75 32 at which the two cam paths are in alignment, under the roller so that the roller will slip readily off one cam track onto the other. The hole 60 is so located in the frame 10 that when the roller is at the point 32, the head 58 of the screw 57 will be disposed centrally of this hole so that the operator of the machine can easily insert a socket wrench or other suitable tool and turn the screw 57.

It has been deemed best to provide a means 80 for locking the cylinder 51 in either of its limit positions. To this end there is mounted in the housing 50 at one side thereof, a spring 85 pressed plunger 62 which is adapted to engage in one or other of the two holes 63 formed in the carrier 51 and corresponding to the limit positions of this carrier. For withdrawing the plunger 62 from engagement with either hole 63 to permit movement of the roller 52, a yoke member 64 is provided. This yoke member 64 is pivoted between a pair of ears 65 formed integral with the housing 50. The shorter arm of the yoke member 64 is slotted at its end and engages under the head 66 of the spring plunger 62. The longer arm of the yoke 64 is bent and bifurcated as clearly shown at 68 in Figures 1 and 2. The furcations extend on either side of the head 90 68 of the screw 57 in a position to be engaged by the socket wrench or other tool employed to move the screw 57 before this tool can be securely engaged with the head 58 of this screw whereby the yoke 64 is rocked about its pivot to withdraw the plunger 62 before the tool is engaged with the head of the screw 95 so that when the tool is firmly engaged with the head of the screw the carrier 51 can be moved. All the time that the tool is engaged with the head of the screw, the plunger 62 will be held in withdrawn position by the 100 105 110 115 120 125 130

volve member, but as soon as the carrier 51 has been moved to its new limit position and the tool has been withdrawn from engagement with the head of the screw, the coil 5 spring 69 will move the plunger 62 into engagement with the adjacent hole 63 to lock the carrier 51 in this new limit position.

From the preceding description, it will be seen that on rotation of the cam shaft 25, 10 which may be driven from any suitable source of power, an oscillating motion will be imparted to the cradle 13, the angular extent of which will be determined in part by which cam the roller 52 is engaged with and in part 15 by the position of the block 44 in the T-slot 45 formed in the arm 36.

As has previously been described, the work 20 spindle on which the gear blank G to be cut is mounted, is journaled in a sleeve which in turn is journaled in the work head. Provision is made for securing to this sleeve a gear segment, the pitch cone angle of which will vary according to the pitch cone angle of the gear to be cut. By suitably selecting the pitch 25 cone angles of the segment which is secured to the sleeve, gears of different pitch cone angles can be generated. In the machine illustrated, the gear segment which is secured to the sleeve is adapted to roll on a relatively 30 stationary gear segment which is mounted upon a relatively fixed part of the machine. Figure 1 shows the work head adjusted to the proper angle to bring the blank G into operative relation with the tools and shows 35 a gear segment 70, which is secured to the sleeve in meshing engagement with the relatively stationary gear segment 71.

In accordance with the principles of co-pending application No. 220,785 above referred to, the work segment 70 will preferably 40 be so selected that its pitch cone angle is less than the pitch cone angle of the gear to be generated and the segment 71 will be a crown gear segment which is resiliently held in mesh with the work segment. By selecting the segments in this way, it has been found that 45 gears of different pitch cone angles can be generated accurately by simply changing the work segment, the resilient mounting of the 50 crown gear segment permitting of the yielding movement required when rolling with work segments of different pitch cone angles.

One feature of the present invention is the 55 improved mounting for the crown gear segment. Secured to the frame 10 of the machine, as by bolts 75 is a bracket 76. Mounted on this bracket 76 for angular adjustment thereon about a point coinciding with the apex of the blank is a standard 77. This 60 standard is guided in its angular adjustment by a lug 78 which engages in a T-slot 79 formed in the upper face of the bracket 76 and it can be secured in any adjusted position by means of the bolts 80 which engage in the 65 T-slot 79 and a bolt 81 which engages in a

T-slot concentric therewith. The crown gear segment 71 is pivotally mounted on the standard 77 being secured by means of screws 84 to an arm 85 which is pivotally mounted on the standard 77 by means of a bolt or stud 70 86. The axis of the bolt or stud 86 is inclined, in the machine shown, to a horizontal plane. In generating bevel gears, the axes of the blank spindle and of the cradle are angularly disposed to each other and intersecting; they 75 lie in the same plane. The axis of the stud 86 is obliquely disposed to this plane which here is horizontal and passes through the apex of the basic crown gear, represented by the tools, to which the gear to be cut is generated conjugate. Through this disposition of the pivotal axis of the crown gear segment, a correct rolling motion is imparted to the blank to correctly generate the tooth profiles. The arm 85 is guided in its pivotal 85 movement about the axis of the stud 86 by means of a gib 88, which is secured to the arm 85 as by means of screws 89 and which engages an arcuate flange or track 90 formed on the standard 77 concentric of the axis of 90 the stud 86.

As will be clearly seen, as the cradle 13 oscillates on its axis, the gear segment 70 will roll on the pivotally mounted crown gear segment 71 thus rotating the sleeve, to 95 which the gear segment 70 is connected, on its axis and since the sleeve is connected to the work spindle through the index mechanism, during cutting, the work spindle will be rotated on its axis. The combined rotation of the work spindle and the oscillation of the cradle impart to the work a rolling movement relative to the tools to generate the tooth profiles.

To maintain the crown gear segment 71 in mesh with the gear segment 70 as they roll together and to permit of the yielding movement required to enable the crown gear segment to roll with gear segments of any pitch cone angle and impart to the work the 105 proper rolling motion, a resilient means is provided for constantly urging the crown gear segment toward the work segment. This means will now be described.

Two separate constructions are shown for 110 holding the work segment and crown gear segment in mesh, one construction, shown in Figures 4, 5 and 6 is particularly applicable where gears are being cut and a gear segment is being used and the other construction is particularly applicable where pinions are being cut and a pinion segment is being used. I shall refer to the construction shown in Figures 4, 5 and 6 first. Each of the segments 71 and 70 are provided with a groove, 115 94 and 95, respectively, arranged parallel to their respective pitch surfaces. These grooves receive, respectively, a pair of rollers 96 and 97 which are adapted to travel in the 120 grooves as the segments roll on each other. 130

- The rollers 96 and 97 are secured, respectively, to a pair of arms 98 and 99 which are pivotally mounted on a stud or bolt 100 which is secured in a bracket 101 which is adjustably secured to the upper face of the cradle 13. 5 The arms 98 and 99 are, respectively, of substantially T-shape, the legs of the T's are pivoted on the stud 100 and one arm of each T carries a roller 95 or 96. The other arms 10 of the T's are provided with a cup shaped recess and between these is interposed a coiled spring 103. This coil spring is heavy enough to maintain the two segments in mesh as they roll together. The bracket 101 is secured to 15 the upper face of the cradle by means of a T-bolt 104 which engages in the T-groove 102 formed in the face of the cradle. A lug may be provided on the bracket 101 for centering it during its adjustment, this lug entering 20 the slot 102. If desired, also, the bracket may be provided with a flange, as clearly shown in Figure 5, extending over the side 25 of the face plate of the cradle.
- Where pinions are to be cut, usually the length of the arm carrying the pinion segment is so short that a groove extending parallel to the pitch surface of the segment could not be provided in this arm. Consequently 30 where the segment connected to the work is a pinion segment, I prefer to use a resilient holding device such as shown in Figs. 7 and 8. Here, 71 again designates the crown gear segment while 70' is the pinion segment, the crown gear segment is grooved as before at 35 95 to receive a roller 105 which is mounted on a lever arm 106 that is pivotally mounted intermediate its length on the stud 107 which is pivotally mounted upon a bracket 108 that can be secured to the face plate of the cradle. 40 The end of the arm 106 opposite to that carrying the roller 105 is enlarged and provided with a cup shaped recess 110. The bracket 108 has formed integral with it an arm 111 which has, also, an enlarged outer end formed 45 with a cupped shape recess 112. Interposed between the two arms 106 and 111 and seated in the cup shaped recesses 110 and 112 is a coiled spring 114. The arm 106 is limited in its pivotal movement about the stud 107 50 under actuation of the spring 114 by means of a bolt 115 which is threaded into the arm 111 and passes through a slot 116 formed in the arm 106 and which carries a nut 117 which serves to limit the outward movement of the 55 arm 106. The spring 114 pressing against the outer arm of the lever 106 serves to constantly urge the roller 105 against the front wall of the groove 95 formed in the crown gear segment 71 to maintain this segment 71 constantly 60 in mesh with the pinion segment 70'. The bracket 108 can be secured in any adjusted position on the cradle by means of bolts 119 which are mounted in the cradle and pass through suitable slots formed in the 65 bracket. A tongue or lug 120 on the bracket 70 75 80 85 90 95 100 105 110 115 120 125 130 135 140 145 150 155 160 165 170 175 180 185 190 195 200 205 210 215 220 225 230 235 240 245 250 255 260 265 270 275 280 to the work spindle. When a gear surface has been generated, the sleeve and work spindle can be disconnected and the work spindle indexed and again locked to the sleeve for generating the next tooth surface.

5 While the present invention has been described in connection with a machine for generating bevel gears, it will be understood that the improvements of the present invention are 10 applicable to other types of gear generating machines, also, as, for instance, to machines for generating hypoid gears. Moreover, while the gear segment arms 70 and 70' have been shown as made in one piece, it will be understood that if desired, these arms may each 15 be made in two parts so that the length of the arms can be adjusted. Through this adjustment, the cone surface of the work segment while rolling on the pitch surface of the crown 20 gear is changeable, so that within limits, one work segment can be used in generating different gears or pinions, as the case may be.

In general, it may be said that while a preferred embodiment of the invention has been 25 described, the invention is capable of various further modifications and uses and that this application is intended to cover any variations, uses, or adaptations of the invention, following, in general, the principles of the invention and including such departures from 30 the present disclosure as come within known or customary practise in the gear art and as may be applied to the essential features hereinbefore set forth and as fall within the scope 35 of the invention or the limits of the appended claims.

Having thus described my invention, what I claim is:

1. In a machine for generating gears, a 40 work spindle, a tool, and means for producing a relative rolling movement between the work spindle and tool including a gear segment connected to the work spindle, a pivotally mounted gear segment, on which the first segment is adapted to roll having a fixed relation to the tool, said pivotally mounted segment being capable of angular motion about its pivot during the rolling movement, and means for resiliently holding the two segments in mesh.

50 2. In a machine for generating gears, a work spindle, a tool and means for producing a relative rolling motion between the work spindle and tool including a gear segment connected to the work spindle, a second gear segment pivotally mounted on a relatively fixed part of the machine on which the first segment is adapted to roll, said second segment being capable of angular motion about its pivot 55 during the rolling movement, and means for resiliently holding the two segments in mesh.

60 3. In a machine for generating gears, a work spindle, a tool, and means for producing a relative rolling movement between the work 65 spindle and tool including a gear segment con-

nected to the work spindle, a second gear segment mounted for rocking movement on a relatively fixed part of the machine on which the first segment is adapted to roll, and means for resiliently holding the two segments in 70 mesh.

4. In a gear generating machine, a tool, a work support, an oscillatable cradle upon which the work support is mounted, a work spindle journaled in the work support, a gear 75 segment connected to the work spindle, a second gear segment, on which the first segment is adapted to roll, pivotally mounted on a relatively fixed part of the machine, said second segment being capable of motion about 80 its pivot during the rolling movement, means for resiliently holding the two segments in mesh, means for oscillating the cradle and means for actuating the tool.

5. In a gear generating machine, a tool, a 85 work support, an oscillatable cradle on which said work support is mounted, a work spindle journaled in said work support, a gear segment connected to the work spindle, a second gear segment, on which the first segment rolls 90 mounted for rocking movement on a relatively fixed part of the machine, means for resiliently holding the two segments in mesh, means for oscillating the cradle and means for actuating the tool.

95 6. In a gear generating machine, a tool, a work support, an oscillatable cradle upon which said work support is mounted, a work spindle journaled in the work support with its axis in the same plane with and angularly 100 disposed to the axis of the cradle, a gear segment connected to the work spindle, a second gear segment pivotally mounted on a relatively fixed part of the machine for angular movement about an axis obliquely disposed 105 to a plane containing the axes of the cradle and work spindle, means for resiliently holding the two segments in mesh, means for oscillating the cradle, and means for actuating the tool.

110 7. In a gear generating machine, a frame, a tool, a work support, a cradle, upon which the work support is mounted, oscillatably mounted in the frame for movement about a horizontal axis, a work spindle journaled in 115 the work support for movement about a horizontal axis angularly disposed to the axis of the cradle, a gear segment connected to the work spindle, a second gear segment, on which the first segment is adapted to roll, pivotally 120 mounted on a relatively fixed part of the machine for angular movement about an axis obliquely disposed to a horizontal plane, means for resiliently holding the two segments in mesh, means for oscillating the cradle and means for actuating the tool.

125 8. In a gear generating machine, a tool, a work support, an oscillatable cradle upon which the work support is mounted, a work spindle journaled in the work support, a gear 130

segment mounted on the work spindle, a second gear segment, on which the first segment is adapted to roll, pivotally mounted on a relatively fixed part of the machine, said second segment being provided with a groove 5 extending parallel to its pitch surface, a roller pivotally mounted on a relatively fixed part of the machine and adapted to travel in said groove as the segments roll together and 10 resilient means resisting pivotal movement of said roller on its support to thereby resiliently hold the two segments in mesh.

9. In a gear generating machine, a tool, a work support, an oscillatable cradle upon 15 which the work support is mounted, a work spindle journaled in the work support, a gear segment secured to the work spindle, a second gear segment, on which the first segment is 20 adapted to roll, pivotally mounted on a relatively fixed part of the machine, each of said segments being provided with a groove extending parallel to their respective pitch surfaces, a pair of rollers pivotally mounted on a relatively fixed support and adapted to 25 travel in said grooves as the segments roll together, and resilient means resisting pivotal movement of said rollers on their support to resiliently hold the two segments in mesh, means for oscillating the cradle, and means 30 for actuating the tools.

10. In a gear generating machine, a work support, a tool support, a cradle upon which one of said supports is mounted, a work spindle journaled in the work support, a toothed 35 member connected to the work spindle, a toothed member having a fixed relation to the tool upon which the first named member rolls, and means for imparting an oscillatory motion to the cradle to produce a relative rolling motion between the tool and blank comprising a pair of cams, a roller engageable 40 selectively with either of said cams and means operatively connecting the roller to said cradle to oscillate the cradle on rotation of the cam with which the roller is engaged, said cams having different contours to impart 45 to the cradle selectively movements of different angular extent.

11. In a gear generating machine, a frame, 50 a work support, a tool support, a cradle oscillatably mounted on the frame and upon which one of said supports is mounted, a work spindle journaled in the work support, a gear segment connected to the work spindle, a gear segment having a fixed relation to the tool upon which the first segment rolls, a cam shaft journaled in the frame, a pair of cams secured to the cam shaft, means for oscillating the cradle on rotation of said cam 55 shaft including a roller operatively connected to the cradle and selectively engageable with either cam, said cams having differently formed cam paths to oscillate the cradle selectively through different sized arcs, the paths 60 of said cams being so formed as to align with

each other at one point, and means for moving the roller from engagement with one cam into engagement with the other when the roller is at the point of alignment of the cam paths.

12. In a gear generating machine, a frame, a work support, a tool support, a cradle oscillatably mounted on the frame and upon which one of said supports is mounted, a work spindle journaled in the work support, a gear segment connected to the work spindle, a gear segment, having a fixed relation to the tool, upon which the first segment rolls, a cam shaft journaled in the frame, a pair of cams secured to the cam shaft, means for oscillating the cradle on rotation of said cam shaft including a roller operatively connected with the cradle and selectively engageable with either cam, said cams having differently formed cam paths to oscillate the cradle selectively through different sized arcs, the paths of said cams being so formed as to align with each other at one point, means for moving the roller from engagement with one cam into engagement with the other when the roller is at the point of alignment of the cam paths, and means for locking the roller in either position of its adjustment and means for automatically unlocking the locking means when a suitable tool is engaged with the means for moving the roller.

13. In a gear generating machine, a frame, a work support, a tool support, a cradle oscillatably mounted on the frame and upon which one of said supports is mounted, a work spindle journaled in the work support, a gear segment connected to the work spindle, a gear segment, having a fixed relation to the tool, upon which the first segment rolls, a cam shaft journaled in the frame, a pair of cams secured to the cam shaft, the larger of which is a closed cam and the smaller of which is an open cam and the paths of which are so formed as to align with each other at one point, means for oscillating the cradle on rotation of said cam shaft including a roller operatively connected with the cradle and selectively engageable with either cam.

14. In a gear generating machine, a frame, a work support, a tool support, a cradle oscillatably mounted on the frame and on which one of said supports is mounted, a work spindle journaled in the work support, a gear segment connected to the work spindle, a gear segment having a fixed relation to the tool upon which the first segment rolls, a cam shaft journaled in the frame, a pair of cams secured to the cam shaft, the larger of which is a closed cam and the smaller of which is an open cam and the paths of which are so formed as to align with each other at one point, means for oscillating the cradle on rotation of the cam shaft including a roller operatively connected with the cradle and selectively engageable with either cam, a car-

rier to which the roller is secured, a screw 5 for moving the roller-carrier in a direction parallel to the axis of the cam shaft from engagement with one cam into engagement with the other when the roller is at the point of alignment of the cam paths, a spring-pressed plunger adapted to engage with one or other of two holes formed in the roller-carrier to secure the roller in either position of its 10 adjustment and a pivoted yoke member, one arm of which is connected with said plunger and the other arm of which extends to a position relative to the head of said screw such that before a suitable tool can be engaged 15 with the head of the screw to rotate the same to move the roller, the tool must engage the yoke and withdraw the plunger from locking position.

16. In a gear generating machine, a tool, 20 a work support, a cradle upon which the work support is mounted, a work spindle journaled in the work support, a bevel gear segment, having a pitch cone angle less than that of the gear to be cut, connected to the 25 work spindle, a crown gear segment, on which the first segment rolls, pivotally mounted on a relatively fixed part of the machine, and means for resiliently holding the two segments in mesh.

17. In a gear generating machine, a frame, 30 a tool mounted on the frame, a work support, a cradle oscillatably mounted on the frame and upon which the work support is mounted, a work spindle journaled in the work support, a gear segment connected to the work spindle, a second gear segment, on which the first segment rolls, pivotally mounted on a relatively fixed part of the machine, means for resiliently holding the two segments in 35 mesh, a cam shaft journaled in the frame, a pair of cams secured to the cam shaft, means for oscillating the cradle on rotation of said cam shaft including a roller operatively connected with the cradle and selectively engageable with either cam, said cams having differently formed cam paths to oscillate the cradle through different sized arcs, the paths of said cams being so formed as to align with each other at one point, and means for 40 moving the roller from engagement with one cam into engagement with the other when the roller is at the point of alignment of the cam paths.

18. In a gear generating machine, a frame, 45 a tool mounted on the frame, a work support, a cradle oscillatably mounted on the frame and upon which the work support is mounted, a work spindle journaled in the work support, a gear segment connected to the work spindle, a second gear segment, on which the first segment rolls, pivotally mounted on a relatively fixed part of the machine, means for resiliently holding the two segments in 50 mesh, a cam shaft journaled in the frame, a pair of cams secured to the cam shaft, the

larger of which is a closed cam and the smaller of which is an open cam and the paths of which are so formed as to align with each other at one point, means for oscillating the cradle on rotation of the cam shaft including 55 an arm pivotally mounted at one end on the frame, an adjustable connecting rod pivotally connected at one end of the cradle and pivotally connected at its opposite end to the arm at the end of said arm remote from its pivotal connection with the frame, and a roller movably mounted on the arm at a point intermediate its ends for selective engagement with either cam when the roller is at the point of alignment of the cam paths. 60

19. In a gear generating machine, a frame, a tool mounted on the frame, a work support, a cradle oscillatably mounted on the frame and upon which the work support is mounted, a work spindle journaled in the work support, a bevel gear segment connected to the work spindle, a crown gear segment, on which the first segment rolls, pivotally mounted on a relatively fixed part of the machine, means for resiliently holding the 65 two segments in mesh, a cam shaft journaled in the frame, a pair of cams secured to the cam shaft having cam paths so formed as to selectively oscillate the cradle through different sized arcs, said paths being so 70 formed as to align with each other at one point, and means for oscillating the cradle on rotation of the cam shaft including a roller operatively connected with the cradle and movable selectively into engagement 75 with either cam.

20. In a gear generating machine, a work support, a stool support, a cradle upon which one of said supports is mounted, a work spindle journaled in the work support, a gear segment connected to the work spindle, a second gear segment, having a fixed relation to the tool, upon which the first segment is rolled, a cam shaft journaled in the frame, a pair of cams secured to the cam shaft, the 80 larger of which is a closed cam and the smaller of which is an open cam and the paths of which are so formed as to align with each other at one point, an arm pivotally connected at one end to the frame, an 85 adjustable connecting rod pivotally connected to the cradle at one end and at its opposite end pivotally connected to the free end of said arm, said arm being provided with a housing intermediate its ends, a member carrying a roller engageable with said cam movable in said housing in a direction parallel to the cam shaft, means for moving the roller carrier in the housing when the roller is at the point of alignment of the two cams and 90 means for releasably securing said roller carrier in either position of its adjustment. 95

21. In a gear generating machine, a tool, a work support, an oscillatable cradle upon which the work support is mounted, a work 100

spindle journaled in the work support, a bevel gear segment, having a pitch cone angle less than the pitch cone angle of the gear to be cut, secured to the work spindle, a crown gear segment, with which the first segment is adapted to roll, pivotally mounted at one end on a relatively fixed part of the machine, means for resiliently holding the two segments in mesh, and means for oscillating the cradle including a pair of cams having cam paths so formed as to oscillate the cradle selectively through different sized arcs, said paths being so formed, also, as to align with each other at one point, and a roller operatively connected with the cradle and movable selectively from engagement with one cam into engagement with the other when the roller is at the point of alignment of the two cam paths.
